UNITED STATES PATENT OFFICE.

ROBERT GRISSON, OF HAMBURG, GERMANY.

CRANK MECHANISM.

SPECIFICATION forming part of Letters Patent No. 601,563, dated March 29, 1898.

Application filed February 12, 1898. Serial No. 670,110. (No model.)

To all whom it may concern:

Be it known that I, ROBERT GRISSON, a subject of the German Emperor, and a resident of Hamburg, in the Empire of Germany, have 5 invented certain new and useful Improvements in Crank Mechanism, of which the following is a specification.

This invention relates to a crank mechanism with a driving-shaft supported eccentrically to the crank-bearing and connected with the crank by a sliding lever.

In order that my invention may be better understood by those skilled in the art to which it appertains, I will proceed to describe the 15 same in detail and for that purpose will refer to the accompanying drawings, wherein—

Figure 1 is an elevation of the improved crank mechanism. Fig. 2 is a like view showing the crank mechanism in another working 20 position, and Fig. 3 is a transverse section on the line I II of Fig. 2.

Similar letters refer to similar parts throughout the several views.

A crank *a* is supported so as to be capable 25 of turning about a bearing *b* by means of a ring *a'*, and the shaft *c* to be turned passes eccentrically through the crank-bearing *b*. The shaft *c* carries an arm or link *d*, which is connected with the crank *a* through the medium of a sliding block *d'*, adapted to move 30 in a slot *a²* in the crank *a*, so that the latter and the link *d* are practically in one plane. The thus-combined crank *a d d'* forms, therefore, in spite of its being composed of several 35 separate parts, a straight crank-arm without laterally-projecting parts.

By this crank mechanism a force acting at the free end of the crank is designed to be utilized as advantageously as practicable. 40 When the mechanism is, for instance, employed for a hand-winch whose drum is arranged upon the shaft *c*, the workman in the usual position of the drum relatively to him can physiologically exert the greatest power 45 during the movement of the crank through its upper path and the smallest power during the movement of the crank through its lower path. By the crank mechanism it is intended that this power shall be fully utilized, which is in fact the case, for during the 50 passage of the crank through its upper path in contradistinction to the passage of the crank through its lower path there is the link *d*, moving at a smaller angular velocity. Accordingly the workman with a slower move-

ment of the link *d* has here to exert his full power, and he may exert less power during the passage of the crank through the lower path with a quicker movement of the lever *d*. These working conditions insure a uniform 60 turning movement of the driving shaft or axle.

The arrangement hereinbefore set forth may also be on two sides with two cranks, which assist each other over their dead-points. 65

The slot *a²* in the crank *a* may be closed or shut up when required by suitable covers or plates *e* of any convenient material—as, for instance, celluloid—as indicated in Fig. 3, so that the link *d* and its sliding block *d'* work 70 in a wholly-closed box. This box, moreover, may be used for lubricating purposes by filling it up with a suitable lubricant or oil. In order that the lubricant may pass from the outer side of the sliding block to the inner 75 for lubricating the bearing and shaft, suitable grooves or perforations *d²* may be provided in the said sliding block.

Having now particularly described and ascertained the nature of my said invention and 80 in what manner the same is to be performed, I declare that what I claim is—

1. The combination with a shaft and a fixed eccentric through which said shaft passes freely, of a crank provided with a bearing for 85 and of greater depth than said eccentric, a link fixed on the shaft within said crank-bearing so as not to project therefrom, a sliding connection between said link and crank and confined within the outer surfaces of the latter, and means for applying power to the 90 crank, for the purpose set forth.

2. The combination with a shaft, and a fixed eccentric through which said shaft passes freely, of a crank provided with a circular 95 bearing for the eccentric, and with a longitudinal slot merging into said bearing, a link a slide-block connected with the link and working in the slot of the crank, and means for closing said slot to form a lubricant-chamber 100 in front of the slide-block, for the purpose set forth.

In testimony that I claim the foregoing as my invention I have signed my name, in presence of two witnesses, this 28th day of January, 1898. 105

ROBERT GRISSON.
